UNITED STATES PATENT OFFICE.

OLAF S. STROM, OF LOS ANGELES, CALIFORNIA, ASSIGNOR TO SOLAR LIGHTING FIXTURE COMPANY, OF LOS ANGELES, CALIFORNIA, A CORPORATION OF CALIFORNIA.

DESIGN FOR AN ELECTRIC-LIGHTING-FIXTURE BRACKET LANTERN.

Application filed December 6, 1928. Serial No. 29,137. Term of patent 3½ years.

To all whom it may concern:

Be it known that I, OLAF S. STROM, a citizen of the United States, residing at Los Angeles, in the county of Los Angeles and State of California, have invented a new, original, and ornamental Design for an Electric-Lighting-Fixture Bracket Lantern; reference being had to the accompanying drawing.

The figure is a side perspective view of a bracket lantern, showing my new design.

I claim:

The ornamental design for an electric lighting fixture bracket lantern as shown.

OLAF S. STROM.
